UNITED STATES PATENT OFFICE

YERMIE G. STERN, OF NEW YORK, N. Y.

DESIGN FOR A DRESS

Application filed October 20, 1931. Serial No. 41,463. Term of patent 3½ years.

To all whom it may concern:

Be it known that I, YERMIE G. STERN, a citizen of the United States, residing at New York city, in the county of New York and State of New York, have invented a new, original, and ornamental Design for a Dress, of which the following is a specification, reference being had to the accompanying drawing, forming part thereof.

In the drawing:

The figure is a perspective view of a dress showing my new design. The back, however, is plain with the exception that the bodice carries the figured design of the cloth of which it is made.

I claim:

The ornamental design for a dress as shown and described.

YERMIE G. STERN.
